UNITED STATES PATENT OFFICE

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

PEDESTAL LEVER FOR PICTURE-PROJECTION MACHINES

Application filed May 31, 1928. Serial No. 281,873.

This invention relates to motion picture projection apparatus, and more particularly to a pedestal lever which is adapted to pivotally support the projection head and the lamp house whereby the angle of projection may be varied in accordance with operating requirements.

The invention provides a pedestal lever having an enlarged base for supporting the projection head and having a downwardly extending flange of rigid construction for pivotally engaging the lamp house support whereby the lamp house may be moved radially thereabout, while the line of projection is maintained parallel in all positions of said lamp house.

The lever is provided with a plurality of sets of horizontally displaced bearings for carrying both the lamp house support and a guiding arm therefor. Means are also provided for pivotally supporting the lever from the pedestal top in such manner that the line of greatest stress passes through the approximate center of the pivotal bearing.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a plan view of the pedestal lever constructed in accordance with this invention showing the lamp house support associated therewith;

Fig. 2 is a side elevation of the lever and lamp house support;

Fig. 3 is a section taken on the line 3—3 of Fig. 2;

Fig. 4 is a section taken on the line 4—4 of Fig. 2;

Fig. 5 is a section taken on the line 5—5 of Fig. 1;

Fig. 6 is a section taken on the line 6—6 of Fig. 5;

Fig. 7 is a front elevation of the pedestal lever;

Fig. 8 is a section taken on the line 8—8 of Fig. 5; and

Fig. 9 is a section taken on the line 9—9 of Fig. 5.

Like reference characters denote like parts in the several figures of the drawings.

In the following description and in the claims parts will be identified by specific names for convenience, but they are intended to be as generic in their application to similar parts as the art will permit.

Referring to the drawings more in detail, the pedestal lever is shown as comprising a body portion 10 having an elongated opening 11 therein for receiving a pedestal arm 12 (Fig. 4), and suitably drilled to receive bolt 13 by means of which it is pivotally held in place between pedestal arms 12 and 14 of pedestal 15. The intermediate portion of section 10 between elongated slot 11 and outer surface 16 is adapted to fit snugly between arms 12 and 14 whereby movement longitudinally of bolt 13 is prevented. Said bolt may be secured as by nut 17 and washer 18.

The pedestal lever is provided at its forward end with a support 20 for the projection head, said support having a plurality of raised surfaces 21 on which the projection head is adapted to rest. Head support 20 is further drilled for receiving clamping screws which are associated with said projection head. Film slot 22 is located in head 20 to provide space for passage of the motion picture film.

Support 20 of the pedestal lever is extended laterally a sufficient distance to contact with the entire under-surface of the projection head. By providing film slot 22 in the supporting surface of the lever the passage of the film is not interfered with and a more rigid support is obtained. Furthermore, support 20 is so designed that the center of stress extends on a line passing midway between arms 12 and 14.

The entire top surface of the pedestal lever is preferably of a width substantially equal

to that of the projection head and bolt 13 is passed transversely through the entire pedestal lever. The bolt may consequently be considered to have two bearing portions, 5 namely, the main bearing surface between arms 12 and 14 which serves to support the greatest portion of the weight of the attached apparatus and an auxiliary bearing surface located externally of said arms which 10 serves to strengthen the apparatus and reduces the tendency of the machine to vibrate. The auxiliary bearing surface also assists in supporting the portion of the projection head which is located adjacent the film slot and in supporting the lever 36 in a 15 manner which will be hereinafter described.

The main support for the lamp house is located midway between arms 12 and 14 in the plane of the center of stress of the projection head. The main weight of the machine is consequently located centrally of the pedestal.

The rear portion of lever 10 includes a downwardly extending flange 23 having a 25 strengthening web 24 and provided with outwardly extending bearing members 25 which are adapted to receive pin 26. Any suitable means may be employed for rigidly securing said pin in bearing members 25, such as 30 screws 27, which are passed through said bearing members into engagement with pin 26.

The upper portion of flange 23 is extended transversely and provided with a pair of outwardly extending bearings 28 which are 35 adapted to receive pin 29. This pin may be secured in said bearings as by set screws 30 (Fig. 2). Lateral strengthening webs 31 extend between bearings 25 and 28 for imparting rigidity to the assembly.

Lamp house support 32 is provided with 40 tubular bearing members 33 which are pivotally engaged by pin 26 and supported thereby. A lamp house base 34 may be pivotally secured to lamp house support 32 as by pin 45 35. A guiding arm 36 is provided at one end with a tubular bearing member 37 in engagement with pin 29, and is adapted to be pivotally connected at its other end to lamp house base 34 as by pin 38.

In the pedestal lever above described, the lamp house is mainly carried by support 32 which is pivotally secured to pin 26, and guiding arm 36 is so connected to the lamp house base as to maintain the same in parallelism as it is pivotally moved about pin 26. The plurality of bearing members 25, however, serve to firmly support the lamp house while permitting the above mentioned 50 pivotal movement. The rigidity of the entire arrangement is increased by strengthening webs 24 and 31 and by the specific location of the lever with respect to pedestal arms 12 and 14. By extending the support 55 for the projection head laterally a sufficient

distance to contact with the entire lower surface of the head and by causing the center of stress to extend in a line between arms 12 and 14, the tendency of the apparatus to vibrate is reduced to a minimum.

The particular form of projection head and lamp house employed form no part of the present invention, and consequently have been omitted for sake of clearness. It is understood, however, that any well known type 70 75 may be employed to advantage with the supporting members above described.

While certain novel features of the invention have been shown and described and are pointed out in the annexed claims, it will 80 be understood that various omissions, substitutions and changes in the forms and details of the device illustrated and in its operation may be made by those skilled in the art without departing from the spirit of the invention. 85

What is claimed is:

1. In a motion picture projecting machine, a supporting pedestal having a pair of arms, a pedestal lever having an elongated slot, 90 means for pivotally mounting said lever on said pedestal whereby one of said arms extends into said slot, and the other of said arms extends externally of said lever, a projection head support carried by the front of 95 said lever, and a downwardly extending flange formed at the rear thereof having means associated therewith for pivotally mounting the lamp house support thereon.

2. In a pedestal lever for a motion picture 100 projecting apparatus, means for pivotally mounting said lever on a supporting pedestal, a projection head support carried by said lever, and means for supporting a lamp house therefrom comprising a downwardly 105 extending flange having a plurality of vertically aligned bearings, a second set of vertically aligned bearings laterally displaced with respect to said first mentioned set, and means associated with each of said bearings 110 for pivotally supporting a lamp house.

3. In combination with a pedestal for a motion picture projecting apparatus, a pedestal lever, vertically aligned bearings carried by said lever for pivotally mounting a 115 lamp house support, means for pivotally mounting said lever to said pedestal, the plane of said vertically aligned bearing extending longitudinally of said lever substantially through the center of said pivotal 120 mounting means, a second set of bearings carried by said lever and located in a longitudinal plane extending outside of said pivotal bearing.

4. In combination with a pedestal for a 125 motion picture projection apparatus, a pedestal lever of a width greater than the top of said pedestal, means for pivotally mounting said lever thereon comprising arms associated with said pedestal, one of said arms 130

extending against the outer surface of said lever, the other of said arms being received in an interior opening thereon, and a pivot bolt passing through said arms and across the entire lever.

5. In a projection machine, a pedestal lever, means for mounting said lever on a supporting pedestal, a projection head support carried by said lever, a lamphouse support having a downwardly extending bracing member, said lever having a flange extending downwardly substantially coextensive with said bracing member and provided with a plurality of vertically aligned bearings, one of said bearings being located at substantially the lower extremity of said bracing member, and means for pivotally mounting said lamphouse support on said bearings.
